UNITED STATES PATENT OFFICE.

SAMSON WATERS, OF LOS ANGELES, CALIFORNIA.

FURNITURE-POLISH.

1,136,742.

Specification of Letters Patent. Patented Apr. 20, 1915.

No Drawing.

Application filed April 23, 1914. Serial No. 833,913.

To all whom it may concern:

Be it known that I, SAMSON WATERS, citizen of the United States, residing at Los Angeles, in the county of Los Angeles and State of California, have invented new and useful Improvements in Furniture-Polish, of which the following is a specification.

My present invention pertains to furniture polishes, and it contemplates the provision of a composition polish which while easily manufactured and inexpensive, is highly efficient in imparting a lasting luster to highly-finished wood-work of all kinds.

15 The invention consists in the composition including the following ingredients, combined in about the proportions stated, viz:

Raw linseed oil	50 per cent.
Coal oil	23 per cent.
Water	23 per cent.
Beeswax	1 per cent.
Banana oil	1 per cent.
Paraffin oil	2 per cent.

25 The ingredients named are to be thor-

oughly mingled by agitation, and the polish is then ready for use.

In using the composition, the piece to be polished is first thoroughly cleansed, and after it is dry the polish is applied through 30 the medium of a soft brush or cloth.

The composition when properly applied is calculated to impart a high finish and a particularly permanent polish or luster to the wooden article on which it is used.

Having described my invention, what I claim and desire to secure by Letters-Patent, is:

The herein described composition of matter for a furniture polish, consisting of linseed oil, coal oil, water, beeswax, banana oil, and paraffin oil, substantially in the proportions described.

In testimony whereof I have hereunto set my hand in presence of two subscribing witnesses.

SAMSON WATERS.

Witnesses:

RALPH WATERS,
HOMER C. WATERS.
